US0D1086656S

(12) **United States Design Patent** (10) **Patent No.:** **US D1,086,656 S**
(45) **Date of Patent:** **** Aug. 5, 2025**

(54) **SANDAL**

(71) Applicant: **Birkenstock IP GmbH**, Linz am Rhein (DE)

(72) Inventors: **Adam Owen**, Linz am Rhein (DE); **Arno Marchand**, Linz am Rhein (DE)

(**) Term: **15 Years**

(21) Appl. No.: **29/970,137**

(22) Filed: **Oct. 25, 2024**

Related U.S. Application Data

(62) Division of application No. 35/518,736, filed on Sep. 29, 2023 (U.S. filing date under 35 U.S.C. 384), and (Continued)
